UNITED STATES PATENT OFFICE.

LINCOLN R. ARNOLD, OF PROVIDENCE, RHODE ISLAND.

RUNWAY.

1,384,114.

Specification of Letters Patent. Patented July 12, 1921.

Application filed November 5, 1920. Serial No. 422,020.

To all whom it may concern:

Be it known that I, LINCOLN R. ARNOLD, a citizen of the United States, residing at Providence, in the county of Providence 5 and State of Rhode Island, have invented certain new and useful Improvements in Runways, of which the following is a specification.

This invention relates to improvements 10 in portable runways of the class adapted to be readily positioned adjacent a curbstone for the purpose of facilitating running a vehicle such as an automobile or the like over the curbstone either in passing 15 from the road to the sidewalk or vice versa; and the object of this invention is the provision of a pair of bridge members each having one end raised to substantially the height 20 of the curbstone and connecting these members together by a pair of spacing arms or bars which are jointed, whereby the members may be folded or swung together adjacent each other to reduce their storing or shipping space.

25 A further object of the invention is the provision of means whereby the working space between these bridge members may be regulated to suit vehicles having different widths.

30 A still further object of the invention is the provision of means whereby the height of the supporting rest blocks may be adjusted so that the raised end of each bridge member may be adjusted to suit curbstones 35 of different heights.

The nature and advantages of the invention will be better understood when the following detail description is taken in connection with the accompanying drawings, the 40 invention residing in the combination and arrangement of parts as claimed.

In the drawings forming part of this specification, like numerals of reference indicate similar parts in the several views and 45 wherein:—

Figure 1 is a perspective view illustrating my improved runway in spaced apart working position adjacent a curbstone.

Fig. 2 is a view of the underside of the 50 bridge members in the runway, showing the centrally pivoted connecting bars or arms in extended position.

Fig. 3 is a detail showing one of the

spring arms as connected to the inner face of the rest block the arm being slotted to 55 permit of endwise adjustment to regulate the working space between the bridge members.

Fig. 4 is a side elevation illustrating the rest block as formed in two parts, one being 60 adjustable relative to the other to regulate the working height of the raised end of the bridge member.

Fig. 5 is an end elevation of the rest block showing the same as formed in two parts, 65 one of the parts being provided with notched inclined grooves whereby one part may be moved upon the other part to adjust the working height of the raised end of the 70 bridge member.

Fig. 6 is a view illustrating the spacing arms as centrally pivoted and folded and the bridge members swung inward adjacent 75 each other to reduce the storing space for a runway and at the same time maintaining their spaced working relations when extended.

With reference to the drawings, 10 designates the pair of bridge members which may be made of any suitable material but which 80 I preferably make of wood, the same being of any desired width and of a suitable length to provide a proper angle for conducting an automobile up over the edge of a curbstone 11.

One end 12 of each bridge member is adapted to rest upon the ground while the opposite end is provided with a suitable rest block 13 for raising and supporting this end at the height of the curbstone 11.

These bridge members are spaced apart and held in proper working position by means of a pair of arms or bars 14, one end of each being connected to the inner face of the rest block while the free ends of these 95 arms or bars are pivotally jointed or hinged together preferably by a pivot bolt 15, which bolt also passes through the ends of a handle 16 by means of which the device may be readily carried about in the hand of the user and then hung up in a convenient place in a garage or barn.

In some instances it is found of advantage to be able to adjust the working length of the connecting arms or bars to accommodate vehicles of different widths. To ac-

complish this in a simple and practical way I have slotted the ends 17 of the bars 14 at 18 longitudinally whereby by loosening the bolts 19 these arms may be adjusted end- 5 wise to regulate their working length.

In still other cases it is found to be of advantage to be able to adjust the rest block so as to regulate the working height of the raised end of the bridge member to accommodate curbstones of different heights.

To accomplish this in a simple and practical way, I have formed the rest block in two parts as illustrated in Figs. 4 and 5, one of the parts 20 being provided with inclined 15 slots 21 the upper edge of which slots are notched as at 22, which notches are engaged by the pins or bolts 23.

By this construction it will be seen that the notches in the edges of these slots serve 20 to engage the pins or bolts 23 and so lock the parts in adjusted position against movement regardless of any strain or weight they may be called upon to withstand.

My improved runway is extremely simple 25 and practical in construction and by its use the bridge members are held in proper spaced apart relation and yet when not in use the whole may be folded into a contracted space to facilitate shipping and storing; then again by this construction the spacing distance between the members may be readily adjusted to suit vehicles of different widths; also the operating heights of the bridge members may be readily adjusted 35 to accommodate different heights of curbstones.

The foregoing description is directed solely toward the construction illustrated, but I desire it to be understood that I re- 40 serve the privilege of resorting to all the mechanical changes to which the device is susceptible, the invention being defined and

limited only by the terms of the appended claims.

I claim:

1. A runway comprising a pair of spaced apart short inclined bridge members each having a rest block at one end for supporting said end the height of a curbstone, and a pair of foldable spacing arms or bars connecting said members whereby said members may be positioned adjacent each other.

2. A runway comprising a pair of spaced apart short inclined bridge members each having a rest block at one end for supporting said end the height of a curbstone, a pair of foldable spacing arms or bars connecting said members whereby said members may be swung inwardly adjacent each other, and means in said arms whereby the spacing of said bridge members may be adjusted.

3. A runway comprising a pair of spaced apart short inclined bridge members each having a rest block at one end for supporting said end the height of a curbstone, a pair of foldable spacing arms or bars connecting said members whereby said members may be swung inwardly adjacent each other, and means whereby the working height of said rest block may be regulated.

4. A runway comprising a pair of spaced apart short inclined bridge members each having a rest block at one end for supporting said end the height of a curbstone, said block being formed in two parts one being provided with notched inclined slots by which said parts may receive relative adjustment for regulating the working height of said block, and a pair of foldable spacing arms connecting said bridge members whereby said members may be positioned adjacent each other.

In testimony whereof I affix my signature.

LINCOLN R. ARNOLD.
